UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ROTARY SNAP SWITCH.

Application filed July 13, 1921. Serial No. 484,353.

My invention relates to rotary snap switches, and particularly to switches of the multi-blade type, the object of my invention being to provide a switch in which the 5 construction and assembly of the insulating body and associated metal parts is simplified, while the current breaking capacity of the switch is also increased.

In the accompanying drawings—

10 Fig. 1 is a plan of a switch in which my invention is embodied in one form;

Fig. 2 is a section on the line 2—2, Fig. 1;

Fig. 3 is a broken plan view of the switch with cover removed;

15 Fig. 4 is a section on the line 4—4, Fig. 3;

Fig. 5 is a section on the line 5—5, Fig. 2;

Fig. 6 is an inverted plan of the switch body; and

20 Fig. 7 is a plan of the base of the switch with the body removed.

In rotary snap switches of multi-blade type, such for instance as that illustrated in the Goodridge Patent No. 1,323,047, it is customary to provide a plurality of switch 25 blades, the contact arms of which lie in different planes and cooperate with switch contacts similarly arranged at different levels on the insulating base. This necessitates a more or less complicated configuration of the base, which is difficult to mold, and, moreover, is apt to lead to confusion in the assembly of contacts in their proper position on the different levels provided for their reception. By my present invention

30 I have simplified the construction by subdividing the insulating body of the switch into two parts, each carrying the switch contacts for their respective levels, the two portions of the base being united in the completed switch. This arrangement enables me to introduce an insulating diaphragm between the switch levels which effectively prevents arcing between the contacts of different levels, and thus increases the current 35 breaking capacity of the switch. The invention may be embodied in various modified forms of construction, but I have illustrated it in the accompanying drawings in a heater switch having certain characteristics in common with those of the switch shown in the Goodridge patent above noted.

40 As here illustrated, the switch comprises an insulating base 10, and a two-part insulating body comprising a block 11 and superposed ring 12, both of insulating ma-

terial. The usual cover 13, with insulating lining 14, is provided to house in the switch.

The base 10 (Fig. 7) carries on its upper face a group of wire terminals 15, 16, 17, 18 and 19, to which the mains and distributing connections may be led through holes 20, 21, 22, 23 and 24 opening through the base adjacent the respective wire terminals. Each of these terminals is tapped at 25 to receive a screw bolt, by which the terminal 60 is connected to its appropriate contact, hereinafter described. The base is also pierced at 26 to accommodate the securing screws 27 by which it is mounted on an appropriate support. The positioning rib 28 is formed 65 on the upper face of the base to properly locate the switch body with respect to the several terminal plates.

The block 11 of the switch body is appropriately recessed at 29 (Fig. 6) on its 70 lower face to receive such portions of the wire terminals as may project above the juxtaposed face of the base, and is also pierced at suitable points 30, 31, 32, 33 and 34 to receive the bolts which establish connection 75 with the several wire terminals.

On the upper face of this block (Fig. 5) are mounted the three lower level switch contacts 35, 36 and 37 which co-operate with the lower blade 38 of the switch mechanism. 80 In addition to the securing screws 39 which pass through the block 11 and take into suitable extensions of the bases of the contacts 35 and 37, both of the latter are connected by their appropriate bolts 40 and 41 85 to their appropriate wire terminals 17 and 15, respectively, to establish electrical connection therewith. The contact 36 is not directly connected to any of the wire terminals, but is connected by bolt 42 (see 90 Fig. 4) to the base of the contact 43 (Fig. 3) carried by the ring 12 of the switch body.

The ring member 12 of the switch body rests upon the outer face of the body block 11 and is appropriately recessed on its juxtaposed face to accommodate the projecting portions of the contacts 35, 36 and 37 which it overlies. On its upper face (Fig. 3) are mounted three contacts 43, 44 and 45, which are not only secured in position by suitable holding screws 46 piercing the ring and base block 11, and taking into their respective bases, but also by screw bolts 47, 48 and 49 passing through the bases and through the corresponding holes 50, 51 and 52 in the 100 105 110

base block 11 to mechanically and electrically connect these contacts to the wire terminals 18, 16 and 19, respectively, on the switch base 10. In order to establish electrical connection between the contact 36 on the block 11 and the contact 43 on the ring element of the switch body, I provide a bushing 53 (Fig. 4) which extends between the bases of these contacts and is clamped between the same by the screw 42 when the ring is assembled in position. Both contacts 36 and 43 are therefore connected to the wire terminal 18. Co-operating with the upper level contacts 43, 44 and 45 carried by the ring 15 is the switch blade 54. If the wire mains be connected to the wire terminals 15 and 16, and the branch connections to the wire terminals 17, 18 and 19, it will be obvious that in the various positions of the switch 20 the current will be distributed to the branch leads in an appropriate manner to control, for instance, the low, medium and high heats of a standard heater unit.

A barrier flange X extending inwardly 25 from the ring 12 is interposed between the upper and lower level blades and switch contacts, and thus effectively prevents arcing between these parts as the switch changes position on its operation. Where the ring is 30 made in one piece it may be necessary to interrupt the barrier flange at suitable points to facilitate its assembly, since it must be slipped between the upper and lower switch blades. Any difficulty in this direction, however, may be readily overcome by forming 35 the ring in two pieces.

The snap switch mechanism may be of 40 standard construction and need not be described in detail. It suffices to point out that that here shown is mounted upon a rotary switch spindle 55, which extends through the cover 13 and has secured to the projecting end thereof the operating thumb piece 56. The latter may be conveniently shaped 45 to afford an indicator cooperating with the legends 57 displayed upon the outer face of the cover. The latter is notched at 58 to engage the rib 28 on the base 10 to accurately 50 position the legends on the cover with respect to the switch mechanism.

It will be noted that the supporting lugs 55 of the contacts 35, 36 and 37 on the insulating body member 11, and the supporting lugs of the contacts 43, 44 and 45 carried by the barrier ring 12 lie on the flat surfaces of both of these members. This is an 60 important consideration, since the position of the contacts may be thus accurately located and the contact construction simplified while the effect of the rugged body structure is maintained when these parts are assembled. Hitherto the location of the switch contacts at different levels has been secured either by recessing the switch body

to afford ledges at different levels, or by 65 providing certain of the contacts with standards of greater length, so that their associated contact blades lie at different levels. The latter construction requires a very 70 heavy and expensive construction of the contacts. The first mentioned construction results in a porcelain of such shape that the lower contact supporting ledges cannot be 75 reached by suitable tools for correcting any errors incidental to the shaping and baking of the porcelains. By sub-dividing the body into the two parts 11 and 12, the two contact supporting faces may be readily machined, if necessary, to present absolutely 80 plane contact supporting surfaces. The simplification of these two elements of the body results in much more perfect porcelains, however, so that such machining is not 85 ordinarily necessary to secure the desired pliancy of the contact carrying faces. Moreover, inasmuch as the contacts are flat, and 90 do not require spacing standards, they may be made of lighter metal, since they are not subjected to the mechanical strains incident to the use of contacts having such standards. 95

Various modifications in arrangement of the switch contacts and switch blades will readily occur to those skilled in the art, without departing from the underlying principles of what I claim as my invention. 95

I claim:—

1. In a rotary snap switch, an insulating body comprising superposed sections and means for uniting the same to form a rigid body unit, the upper surfaces of said sections lying in planes capable of being machined, upper and lower banks of contacts mounted on said surfaces, in combination with a switch spindle, and upper and lower banks of switch blades thereon cooperating with the said contacts, the engaging surfaces of said blades and contacts lying in planes substantially normal to the axis of the switch spindle. 100

2. In a rotary snap switch, an insulating body comprising superposed sections and means for uniting the same to form a rigid body unit, the upper surfaces of said sections lying in planes capable of being machined, upper and lower banks of contacts mounted 105 on said surfaces, in combination with a switch spindle, and upper and lower banks of switch blades thereon cooperating with said contacts, the engaging surfaces of said blades and contacts lying in planes substantially normal to the axis of the switch spindle, together with an insulating barrier associated with the upper body section and interposed between said upper and lower contact banks. 110

In testimony whereof I have signed my name to this specification.

GEORGE B. THOMAS.
